UNITED STATES PATENT OFFICE.

JOHN HENRY PETERS, OF DARLINGHURST, NEAR SYDNEY, NEW SOUTH WALES,
AUSTRALIA.

CONCRETE MIXING AND SPREADING MACHINE.

Application filed January 27, 1923. Serial No. 615,254.

To all whom it may concern:

Be it known that I, JOHN HENRY PETERS, subject of the King of Great Britain and Ireland, residing at Rosebank Avenue, 5 Darlinghurst, near Sydney, in the county of Cumberland and State of New South Wales, Australia, have invented certain new and useful Improvements in Concrete Mixing and Spreading Machines, of which the following is a specification.

This invention relates to machines for mixing and spreading concrete, and it has been particularly devised for the purpose of spreading the mixed concrete on prepared 15 road beds to pave the same with a minimum of manual labour. It is usable also for laying concrete floors of large area, for paving water channels and for moulding concrete sleepers, posts, and lintels in moulds or in 20 partitioned moulds which are placed below it. The machine comprises a chassis or frame which for road and floor laying purposes is mounted on wheels adapted to run on a temporary track consisting of rails laid 25 at either side of the surface to be paved, a concrete mixer mounted on said chassis, and a spreader or screed for spreading and strickling concrete which is gravitationally deposited directly from the pan on to a road 30 bed or pavement or into moulds set below the machine. The machine includes an assembly of mechanical devices for operating mixing rake-spades in the pan, for adjusting said spades for various purposes, for 35 traversing the screed, and optionally for propelling the chassis, appropriate controls being provided to enable the operator to manually command these several operations. Accessory devices consist in mechanism for 40 manipulating the water supply, for controlling the motive power unit which is installed on the chassis, and for other purposes incidental to the operation of the machine in practice. The mixing pan and its parts 45 include features which are of substantial practical value for the making of concrete otherwise than for paving purposes, and it is to be understood, therefore, that the mixing pan and its equipment is to be regarded as a separable unit of the complete 50 apparatus which may be installed in connection with other apparatus, or used without other apparatus for the purpose of producing a concrete mixture for building and 55 other operations.

In the accompanying drawings,—

Fig. 1 is a top plan of the machine;

Fig. 2 is a rear end elevation of the machine with the finished surface of a crowned road bed indicated in a dotted line; 60

Fig. 3 is a transverse section looking rearward on the line 3—3 Fig. 1;

Fig. 4 is a longitudinal section on the line 4—4 Fig. 1;

Fig. 5 is a plan view of one of the filling 65 hoppers as it appears when canted as suggested in Fig. 3;

Fig. 6 is an elevational view showing the pan with a tilting mounting which is provided for the purpose of enabling it 70 to be set horizontally to ensure satisfactory operation when the machine is working on a grade; this view is taken on the line 6—6 Fig. 1;

Fig. 7 is a fragmentary detail view on enlarged scale explanatory of trip mechanism 75 for reversing the screed movement, and showing also the method of mounting the screed on a beam frame across one end of the machine;

Fig. 8 is an end elevational view corresponding with Fig. 7;

Fig. 9 is a fragmentary perspective view explanatory of the detail of the mechanism for setting and tilting the mixing rake- 85 spades which operate in the pan; and

Figs. 10 and 11 are fragmentary detail views of portions of certain of the parts which are shown also in Fig. 9.

The chassis 20 is a frame structure of 90 sectional steel, gusset stayed at various points to stiffen it, and mounted on two axles 21—21 which are fitted with wheels 22, which may be flanged wheels as shown adapted to run on rails 23 or may be plain 95 faced wheels adapted to run on a flat track-way. On the forward part of the chassis, an internal combustion engine 24 is mounted; this engine, for which an electric motor may be substituted when the conditions of use 100 so permit, supplies the necessary motive power for all the operations of the machine including optionally the progressive movement of the chassis 20 along the rails 23 or other track. A drive connection for moving the chassis is not shown in the drawing. An alternative drive device consisting of a crank handle 25 is shown which operates through a worm 26 on a worm wheel 27 keyed to the forward axle 21. When power 105 110

drive is required the shaft 32 is geared to the forward axle 21. The main shaft 28 of the motor transmits drive through a worm and worm wheel 29 to a jack shaft 30 which is 5 geared by a chain 31 working over drive sprockets to a fore-and-aft shaft 32. A dog clutch 33 on the shaft 32 is engageable with a bevel pinion 34 which is in gear with a bevel pinion 35 keyed on a countershaft 36 10 running transversely of the machine. A spur wheel 37 is keyed to the same shaft 36, and with this spur wheel 37 a spur pinion 38 is geared, said pinion being keyed on a hand crank shaft 39 to the squared end 15 40 of which a hand crank may be fitted when required. On the inner end of the shaft 36 is keyed a bevel pinion 42 housed in a bearing casing 43 fixed on the chassis. With this pinion 42 a bevel wheel 44 is in gear; this bevel 20 pinion is keyed on a vertical spindle 45 which passes up through the circular central bottom plate 46 on the base of the pan 41, a conical box 47 being fitted to protect the spindle 45 and prevent concrete or slop finding its way into the footstep or bearing 25 journals. On the top end of the shaft 45 sweep arms 48 are fixed. The ring wall 49 of the pan is supported by trunnions 70 on the chassis. The annular bottom space between 30 the centre bottom plate 46 of the pan and its walls 49 is filled with a floor plate 50 covered with a false floor plate 51; the latter may be in sections fixed in so that they 35 may be readily removed for replacement. A single floor plate may be used instead of the double plates 50-51, but it is preferred to use the false flooring in order to minimize cost of replacement.

Another dog clutch 52 is fitted near the 40 rear end of the shaft 32; this dog clutch is engageable with its counterpart member 53 which is freely rotatable on the shaft 32 when the clutch is disengaged. The member 53 is fixed to a sprocket wheel 54 which 45 is geared by a chain 55 to another sprocket 56 on a jack shaft 57; this jack shaft is mounted in bearings 58 on the frame, and it carries a sprocket pinion 59 over which the screed chain 60 runs. At the other side 50 of the machine the screed chain 60 runs over an idle sprocket 61. 62 and 63 are housing boxes which protect the projecting gears.

65 is a water tank which is mounted on stanchions 66 upstanding from the frame 55 above the top level of the pan sides 49. A water delivery service 67 from the tank 65 is controlled by a hand valve 68. The pipe 67 is brought round to the side of the structure and returned over the middle of the 60 pan, its incoming portion 69, which is radial to the pan, is perforated to deliver a spray of water over the material contained in the pan during the mixing operation. The perforations are large and set closely over the 65 middle portion of the pan in order that the

dry material which is dumped into that portion of the pan will be rapidly wetted down and the mixing of it thus facilitated. The pan trunnions 70 are arranged to permit the pan to be tipped forwardly or rearwardly 70 in fore-and-aft direction so that it may be operated in a horizontal position notwithstanding that the machine is working on a grade. The adjusting means consist of two screws 71 fixed in lugs 72 on the pan sides 75 49; the points of these screws bear on the chassis frame 20.

The sweep arms 48 on the top end of the spindle 45 carry the mixing rake-spades 74 and 75. Rake-spades (preferably three as 80 shown) are fitted on each arm; the rake-spades (75) on one arm being pitched to sweep the mixture in the pan towards its periphery, and those (74) on the other arm being angularly pitched to sweep the mixture inward toward the centre of the pan. The outward pitched driving rake-spades 75 are set at a faster pitch than the rake-spades 74 in order that they will move the mixture more rapidly than the inward 90 pitched rake-spades 74, thereby to ensure delivery of mixed concrete through the scupper chute 76 which depends from the pan bottom and is arranged to deposit the delivered mixture on the road bed or into moulds 95 77. The rake-spades are carried on independent floating arms 79. They are each fitted on a helve 80 by two bolts one of 100 which passes through a slotted hole 81 to permit crosswise angular adjustment of the spade on the helve. The helve heads are rotatably fixed in T sockets 82 which are 105 fixed on the outer ends of the floating arms 79, and they carry slotted quadrants 83 by which the angular disposition of the spades in relation to the radii of the pan may be adjusted by means of pinching bolts 84 which pass through the slots 85 in 110 said quadrants. Each of the arms 79 has its downward motion limited by an adjustable check screw 87 which passes through a lug 88 on a T shoulder 89 which carries the inner end of the arm 79 rotatably on one of 115 the sweep arms 48.

The sweep arms 48 may be tubular as 120 shown or they may be solid. They are sheathed with tubes 90 which are rotatable on them; the sheath tubes 90 extend up to 125 fixed collars 97, which are provided with lugs 96 in which a key 98 may be inserted for a purpose hereinafter to be described. On each end of both arms 48 end collars 93 are fixed. Upon these end collars check beams 92 are mounted. The shoulder T's 89 of the floating arms 79 are rotatable on the sleeves 90 so that these arms may be raised and lowered. A hand lever 94 extends from a collar 95 which is mounted for rotation 130

on each tube 90, and a pin 99 offset from the side of this lever carries a pawl 100 which is engageable with detent teeth on a collar 101 which is keyed to the tube 90. Upon the 5 beam 92 a swinging check 106 is provided to co-act with each of the adjusting stop screws 87. When any one of the arms 79 is lifted the check 106 may be swung in behind the point of the adjusting screw 87 so as to hold 10 the arm tipped up slightly as shown in Fig. 10, or when so required tipped up at a steep angle as shown in Fig. 11, thereby to hold the rake-spade on the end of it clear above the material in the pan. From each of the 15 detent collars 101 a lever arm 102 extends downwardly; these arms carry between them a pull bar 103 which may be tubular as shown. Tension springs 104 connect the bar 103 with the movable lugs 105 which are 20 fixed to the floating arms 79. The springs 104 function to pull the arms 79 downward so as to hold the rake spades 74 in the mixing mass of concrete. To facilitate the lifting of the arms 79 to clear the rake spades 25 from the mixing mass, the tension on the springs 104 must be released. Tension is applied to the springs 104 by engaging the pawl 100 with the detents on the collar 101 and then rotating the collar by means of the 30 lever arm 94 thereby to move the pull bar 103. The lever arm 94 is then locked in the tensioned position by inserting the check key 98 in the hole in the lug 96. When the lever 94 is freed the detent collar 101 is no 35 longer held, and it rotates and allows the bar 103 to move forwardly to release the tension of the springs 104. It is to be understood that a separate spring pull attachment may be provided for each one of the 40 arms 79 so as to make the adjustment for each of them independent. The arrangement described and indicated in the drawings provides for the control of the gang of three arms by a pair of levers 94 one located 45 at either end of the three arm assembly. In the case of independent control of the several arms in the gang, the tail of each spring 104 is connected directly to the arm 102 on the detent collar 101, associated with its 50 particular arm or alternatively the lever and detent device may be omitted and the bracket arm 102 may be fixed directly on the sweep arm 48, and tensioning of the spring 104 then effected by moving the clamp collar 105 along the floating arm 79 and fixing it 55 on said arm when its position has been so adjusted.

In the full down position of the rake spades the stop screw 87 contacts directly 60 with the back of the beam 92. The bottom edges of the spades are then just clear of the pan floor. In the partially raised position of the rake-spades the stop screw 87 bears on the flat of the swinging stop 106, 65 and when they are fully lifted so that they

set clear above the material in the pan the stop screw 87 is engaged against the knob 107 on the swinging lug as shown in Fig. 11.

By means of the adjusting mechanisms which have been described, the rake-spades 70 may each be set for vertical position in the pan and for angular direction and longitudinal set, and the tension under which the rake-spades are held down in the mixing mass is also adjustable, and facilities are 75 provided for holding any one or more of the rake-spades either partially or fully lifted without interfering with the adjustments of the other rake-spades.

The rake-spades are concave on the face 80 and the outermost of the insweeping spades 74 is located near the pan wall to ensure that concrete will not bank up around the wall and remain there. The direction of movement of the rake-spades is indicated by 85 arrows.

The screed blade 77 operates transversely under the chassis frame. It traverses over the road bed with an adjusted clearance depending upon the thickness of concrete paving to be laid. This adjustment is effected by laying the rails 23 to a predetermined height above the prepared road or paving bed 110. 111 represents a paving layer of 90 concrete on which the screed has operated. The steel plate screed blade 77 is mounted in cheeks 112 which are hung on a wrist pin 113 fixed in the screed carriage 114. Pivot lugs 115 on said carriage take behind stops 116 on the screed blade 77. The 100 pivot lugs 115 are forked as shown at 130, and a clearance notch 131 is cut in the top edge of the screed plate 77 to allow it to swing laterally freely when the pivot lugs 115 are canted outward to the clearance position shown in Fig. 8. The lugs 115 are moved by a throw bar 132 which extends across the machine and is formed with cranked ends pivotally mounted in fixed 110 bearings 133; one end of it is extended through one of the bearings 133 and is fitted with a hand lever 134. When the hand lever 134 is thrown to bring the lugs 115 to erect position as shown in Fig. 4, the screed blade 77 is held erect. When the 115 hand lever 134 is thrown oppositely to cant the pivot lugs 115 to the free position shown in Fig. 8, the screed blade 77 is freed to swing on its wrist pin 113 so that it may trail across the paving and not operate to 120 strickle the paving as when it is held erect in the Fig. 4 position. This freedom to trail is necessary to enable the workmen to control the distribution of the concrete to bring it toward one side or other of the bed to 125 procure evenness in the work. The screed carriage 114 runs on a beam guide 118; guide wheel runners 119 working between the flanges of the beam 118 being fitted to minimize friction. The guide beam 118 130

is curved or straight according to the finish line of the work, and it is mounted on the frame by bolts passing through slotted holes, in order that it may be adjusted with one end of it higher than the other to facilitate the paving of crowned roads in two courses, pitched respectively to the two sides of the roadway.

A slotted extension member 120 on the screed carriage 114 carries in the slot in it two sprocket wheels 121 and 122. To the sides of these sprocket wheels are fixed detent check wheels 123—124, the direction of the toothing in these detents being opposite. The continuous chain 60 through which motion is transmitted to the screed carriage, runs always in one direction, as indicated by the arrow (Fig. 7). Upon the bracket extension 120 a striker arm 125 is mounted on a pivot 126. This striker is fitted with pawl arms 127 and 128, which respectively engage the detent wheels 123 and 124. The stem of the striker 125 is embraced by a fork 140 pivotally carried at 126 on the member 120. This fork also engages a throw bar 141 extending across the machine, cranked at its ends, and mounted in end bearings 142 through one of which it is extended, a hand lever 143 being fitted on the extended end. When the hand lever 143 is thrown in one direction to bring the fork 140 downward, the striker is moved to the position shown in Fig. 7, in which position its pawl 127 engages the detent 123 and its pawl 128 is disengaged from the detent 124. The chain 60, which is guided under the idle rollers 150 on the top of the carriage extension 120, then operates to drag the carriage towards the left, so moving the screed blade towards the left. At the end of the left traverse movement, the bent portion 129 of the arm 125 encounters a stop 137 (see Fig. 2), which forcibly throws the striker arm 125 and releases the pawl 127 and engages the pawl 128 with the detent check wheel 124, so preventing overrunning and breakages, and causing the carriage to be traversed to the right carrying the screed with it. Similarly, at the end of the right hand movement the striker 125 is automatically reversed by contacting with another fixed stop 138 and the carriage is then caused to move from right to left. An alternating traverse movement of the carriage and screed is thus obtained from the uni-directional movement of the chain 60, and the concrete which is deposited on the road bed through the scupper chute 76 from the pan is spread across the road bed or on a prepared surface or in moulds set under the machine and is strickled to a smooth finish.

The pan is charged intermittently through two tilting hoppers 160—161. Two hoppers are fitted to enable loading to be carried on

simultaneously from either side of the machine. A proportioned charge of Portland cement, sand, and stone aggregate is thrown on to the low side of either hopper, and when thus loaded the hopper is canted over to reverse position, whereupon the charge slides down the hopper floor and passes through the hopper scupper 162 onto the distributor 181 over the center of the pan, whence it falls dispersed into the pan. It is to be understood, however, that the pan may be charged by conveyors of mechanical or pneumatic type, either intermittently or continuously. The water flow through the pipe 69 is regulated according to the rate of loading so as to procure proper wetness of the mixture which is being produced in the pan. As the rake-spades are revolved around the pan the mass is thoroughly mixed, alternate inward and outward sweeping motion being applied to it by means of the rake-spades, with a tendency for the mixed material to heap up towards the edge of the pan. As the rake-spades 75 pass over the lip of the scupper chute 76 they sweep the mixed concrete therethrough and it falls by gravity on to the prepared surface or mould and is spread and strickled as the machine is progressed forwardly along its track.

This machine constitutes an economical equipment for the building of concrete roads inasmuch as a minimum of supervision and labour is required, and uniform work is produced at a rapid rate. As the diameter of the pan will correspond substantially with the dimensions of the machine—in other words will correspond with the width of paved track to be laid—a machine of appropriate size will effect the paving of substantially uniform lengths of road irrespective of width in unit time. The preparation of the road bed is effected by any known apparatus or method. When concrete paving has been laid and strickled by this machine it is allowed to set and season for a period of 21 days or more, and if desired, may, before being used for traffic, be surfaced with a wash of bituminous material.

It will be understood that the prepared road bed may be partially paved with loose sets or stones before the machine is passed over it to fill it and to surface it with concrete.

What I claim as my invention and desire to secure by Letters Patent is:—

1. Apparatus for the purpose set forth, comprising a wheeled chassis, a beam guide mounted transversely on said chassis, a carriage mounted on said guide and traversible thereon, a screed pendularly hung across said carriage and adapted to spread and strickle concrete delivered on to a prepared surface, shaft, clutch, and control gearing

for traversing said screed carriage, a lock for holding said screed in a rigid vertical position, means for releasing said lock to permit the screed to trail in either direction, 5 and means for reversing the direction of the traversing movement of the screed carriage.

2. In apparatus according to claim 1, means for locking and releasing the screed, 10 said means consisting of forked lugs pivotally mounted on the carriage across which said screed is pendularly hung, a bar with cranked ends extending across the chassis and adapted to throw said lugs in one direction to lock the screed in a rigid vertical position and in the opposite direction to release the screed to trail in either direction.

3. In apparatus according to claim 1, 20 means for traversing the screed carriage, said means consisting of a flanged beam guide mounted transversely on the chassis, wheels mounted on said carriage and running between the flanges of said guide, a 25 continuous chain running over sprockets mounted at opposite sides of the chassis, shaft, clutch and control gearing for driving said sprockets, two sprocket wheels mounted one above the other in said carriage and engaging said chain, oppositely toothed detents fixed to the sides of said sprocket wheels, and means including a 30 striker for alternately engaging the carriage with the upper and lower run of the 35 said chain for the purpose of imparting alternating traversing movement to the carriage.

4. In apparatus according to claim 1, 40 means for reversing the direction of the traversing movement of the screed carriage, said means comprising a flanged beam guide mounted transversely on the chassis, wheels mounted on said carriage and running between the flanges of said guide, a continuous 45 chain running on sprockets mounted

at opposite sides of the chassis, shaft, clutch and control gearing for driving said sprockets, two sprocket wheels mounted one above the other in the carriage and engaging said chain, oppositely toothed detents 50 fixed to the sides of said sprocket wheels, a striker pivotally mounted on the carriage, pawl arms fixed on said striker and adapted to engage the upper and lower detent respectively, a fork integral with said 55 striker, a bar with cranked ends extending across the chassis and engageable by said fork, means for rocking said bar and said fork so that engagement and disengagement of the pawl arms with the opposing detents 60 is alternated, and the screed carriage movement is reversed.

5. In apparatus according to claim 1, means for automatically reversing the direction of the traversing movement of the 65 screed carriage, said means comprising a flanged beam guide mounted transversely on the chassis, wheels mounted on said carriage and running between the flanges of said guide, a continuous chain running on 70 sprockets mounted at opposite sides of the chassis, shaft, clutch and control gearing for driving said sprockets, two sprocket wheels mounted one above the other in the carriage, and engaging said chain, oppositely toothed detents fixed to the sides of 75 said sprocket wheels, a striker pivotally mounted on the carriage, pawl arms fixed on said striker and adapted to engage the upper and lower detent respectively, a fork 80 integral with said striker, fixed stops at opposite sides of the chassis engageable with the striker at the limit of the movement of the carriage in either direction and adapted to automatically reverse the position of the 85 said striker and said pawl arms in relation to the upper and lower detent in the screed carriage.

In testimony whereof I affix my signature.
JOHN HENRY PETERS.
